US0D1009921S

(12) **United States Design Patent** (10) **Patent No.:** **US D1,009,921 S**
(45) **Date of Patent:** **** Jan. 2, 2024**

(54) **DISPLAY SCREEN OR PORTION THEREOF WITH GRAPHICAL USER INTERFACE**

(71) Applicant: **Apple Inc.**, Cupertino, CA (US)

(72) Inventors: **Samuel Howard Bebbington**, London (GB); **Lee Broughton**, Santa Cruz, CA (US); **Gary Butcher**, Los Gatos, CA (US); **Alan C. Dye**, San Francisco, CA (US); **Jonathan P. Ive**, San Francisco, CA (US); **Pedro Mari**, Santa Cruz, CA (US); **Pani Page**, Sunnyvale, CA (US); **Aled Williams**, Llandeilo (GB); **Christopher Wilson**, San Francisco, CA (US)

(73) Assignee: **Apple Inc.**, Cupertino, CA (US)

(**) Term: **15 Years**

(21) Appl. No.: **29/853,768**

(22) Filed: **Sep. 19, 2022**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The outermost broken lines in the figures show a display screen or portion thereof, and form no part of the claimed design. The other broken lines in the figures show portions of the graphical user interface that form no part of the claimed design.

1 Claim, 2 Drawing Sheets
(1 of 2 Drawing Sheet(s) Filed in Color)

Related U.S. Application Data

a continuation of application No. 29/777,269, filed on Apr. 5, 2021, now Pat. No. Des. 930,693, which is a continuation of application No. 29/608,792, filed on Jun. 26, 2017, now Pat. No. Des. 915,430, which is a continuation of application No. 29/567,733, filed on Jun. 11, 2016, now Pat. No. Des. 790,588.
